(57) CLAIM

The ornamental design for a vacuum cleaner base, as shown and described.

DESCRIPTION

FIG. 1 is a front, right perspective view of a vacuum cleaner base showing our new design;

FIG. 2 is a front view thereof;

FIG. 3 is a left side view thereof;

FIG. 4 is a right side view thereof;

FIG. 5 is a top view thereof; and,

FIG. 6 is an enlarged view of the detail in FIG. 4.

The details shown in broken lines form no part of the claimed design.

1 Claim, 6 Drawing Sheets
